H. C. PRIEBE

RUNG

Filed Dec. 21, 1923

UNITED STATES PATENT OFFICE.

HERMAN C. PRIEBE, OF BLUE ISLAND, ILLINOIS.

RUNG.

Application filed December 21, 1923. Serial No. 682,124.

To all whom it may concern:

Be it known that I, HERMAN C. PRIEBE, a citizen of the United States, residing at Blue Island, in the county of Cook and State 5 of Illinois, have invented a certain new and useful Improvement in Rungs, of which the following is a full, clear, concise, and exact description.

My invention relates to rungs serving as 10 hand holds, foot holds, and other purposes.

The invention has for its object the provision of an improved rung structure capable of ready assembly with its support and which is so shaped that it may hold itself 15 in proper position with respect to its support in readiness for use.

The rung structure of my invention includes an element of loop form, one side of the loop serving as the rung proper and the 20 complementary side serving as the means whereby the rung may be mounted.

In the preferred embodiment of the invention the loop element of the rung structure is formed of a rod suitably bent to clear 25 its rung portion when the structure is assembled with its support. I desirably provide an eye upon the outer end of one loop side and extend the other loop side beyond this eye, there desirably being a bolt formed with 30 an eye that receives the latter loop side and having a stem projecting through the eye upon the loop. A nut is screwed upon this stem to hold all of the parts in assembly with the support or mounting therefor.

The rung structure of my invention is 35 well adapted for use in the formation of freight car ladders and hand holds.

The invention may be of particular service in connection with refrigerator cars in 40asmuch as the rung structure of my invention may be assembled therewith without the necessity of employing bolts which penetrate the inner walls of the cars.

The invention will be more fully explained in connection with the accompanying drawing in which Fig. 1 is a view in elevation of an end portion of a freight car having rung structures of my invention assembled therewith in a manner to form a 45 ladder; Fig. 2 is a sectional view on line 2—2 of Fig. 1, on a larger scale; Fig. 3 is a sectional view on line 3—3 of Fig. 1, on a larger scale; Fig. 4 is a view of the rung structure and its assembling bolt with

the parts in separated relation; and Fig. 5 55 is a sectional view on line 5—5 of Fig. 3, on a larger scale.

Like parts are indicated by similar characters of reference throughout the different figures.

I have illustrated my invention as applied to a freight car of which an end portion 1 is illustrated though the invention is not to be limited to any particular use. A vertical series of rungs 2 is assembled 65 with the car to form a ladder though it is understood that the rung structures of my invention may be singly assembled with the car 1 or other support in a manner to constitute a hand hold as well as a foot hold. 70

Each rung 2 is constituted of one side of a loop, as illustrated most clearly in Fig. 4. This loop side 2 has an angular section 3 at its outer end and an eye 4 at the outer end of this section and angular 75 to the plane of this loop side and its said section, the eye being disposed to have its axis perpendicular to the loop sides. The base of the loop includes one section 5 which is angular and contiguous to the 80 loop side 2 and extends therefrom in a direction generally similar to the direction in which the aforesaid section 3 projects from this loop side. A continuing section 6 in the base of the loop connects the section 5 with an additional continuing section 7. The loop section 6 is angular to the plane in which the portions 2, 3, and 5 lie and therefore elevates the section 7 above 85 this plane. This section 7 forms a minor 90 loop in conjunction with the loop side 8 and its angular base extension 9. The loop side 8 is continued beyond the eye 4 and is passed through the eye 10' of a bolt 10 whose shank passes through the eye 4. 95 This bolt shank is desirably threaded to receive an assembling nut 11.

In assembling the rung structure with its support the loop side 8 is inserted through or to the rear of the support and the assembling bolt is placed with its eye 10' to receive this loop side and with its stem projecting through the eye 4 to receive the nut 11 which maintains the parts in assembly. The minor loop formed by the parts 7, 8 and 9 embraces 100 one side of the support as illustrated most clearly in Fig. 2. The angular sections 3 and 5, in conjunction with the eye 4 and

the section 6 maintain the rung 2 suitably spaced apart from the support to accommodate the hand or foot.

In refrigerator car construction, the loop side 8 of each rung structure is passed through the timbers 12 and 13 and each bolt is placed with its eye 10 within the timber 12 and with its threaded stem projecting outwardly beyond the car to be received within the corresponding eye 4 and to receive the complementary nut 11 that is relied upon to maintain all of these parts in assembly with their support. The car is formed with an elongated opening 14 through which the bolt eye 10' is passed, this opening being afterwards filled by a plug 15. The rung assembling bolts thus do not need to extend into the interior of the car which is an advantage in refrigerator car construction.

It is obvious that changes may be made without departing from the spirit of my invention.

Having thus described my invention I claim as new and desire to secure by Letters Patent the following:—

1. A rung structure including one element in the form of a loop having an eye at the outer end of one of its sides and whose other side is continued beyond said eye; a second element in the form of a bolt having an eye receiving the latter loop side and a threaded stem passing through the eye upon the first element; and a nut threaded upon the bolt stem.

2. A rung structure including one element in the form of a loop having an angular section at the outer end of one of its sides and an eye at the outer end of this section and angular to the plane of said loop side and this section and whose other side is continued beyond said eye; a second element in the form of a bolt having an eye receiving the latter loop side and a threaded stem passing through the eye upon the first element; and a nut threaded upon the bolt stem.

3. A rung structure including one element in the form of a loop having a section in its base portion contiguous and annular to one loop side and an eye on the outer end of this loop side angular to the plane of said loop side and base section, the other side of the loop being continued beyond the eye; a second element in the form of a bolt having an eye receiving the latter loop side and a threaded stem passing through the eye upon the first element; and a nut threaded upon said stem.

4. A rung structure including one element in the form of a loop whose base includes one section angular and contiguous to one loop side and a continuing section angular to the plane of this loop side and base section and also having an eye angular to and at the outer end of this loop side, the re-

mainning side of this loop being continued beyond this eye; a second element in the form of a bolt having an eye receiving the latter loop side and a threaded stem passing through the eye upon the first element; and a nut threaded upon said stem.

5. A rung structure including one element in the form of a loop whose base includes one section angular and contiguous to one loop side, a continuing section angular to the plane of this loop side and base section, and an additional continuing section angular to the aforesaid continuing section and forming a minor loop with the adjacent portion of the remaining loop side, the first loop side having an eye at its outer end that is also angular to the aforesaid plane and beyond which the aforesaid remaining loop side is continued; a second element in the form of a bolt having an eye receiving said remaining loop side and a threaded stem passing through the eye upon the first element; and a nut threaded upon said stem.

6. A rung structure including one element in the form of a loop having an angular section at the outer end of one of its sides and an eye at the outer end of this section and angular to the plane of said loop side and this section and a section in its base portion contiguous and angular to the aforesaid loop side and extending therefrom in a direction generally similar to the direction in which the first aforesaid section projects from said loop side, the other side of the loop being continued beyond the eye; a second element in the form of a bolt having an eye receiving the latter loop side and a threaded stem passing through the eye upon the first element; and a nut threaded upon said stem.

7. A rung structure including one element in the form of a loop having an angular section at the outer end of one of its sides and an eye at the outer end of this section and angular to the plane of said loop side and this section and whose base includes one section angular and contiguous to the aforesaid loop side and extending therefrom in a direction generally similar to the direction in which the first aforesaid section projects from said loop side, and a continuing section angular to the plane of this loop side and base section the remaining side of this loop being continued beyond this eye; a second element in the form of a bolt having an eye receiving the latter loop side and a threaded stem passing through the eye upon the first element; and a nut threaded upon said stem.

8. A rung structure including one element in the form of a loop having an angular section at the outer end of one of its sides and an eye at the outer end of this section and angular to the plane of said loop side and this section and whose base includes one section angular and contiguous to the

10 aforesaid loop side and extending therefrom in a direction generally similar to the direction in which the first aforesaid section projects from said loop side, a continuing section 5 angular to the plane of this loop side and base section, and an additional continuing section angular to the aforesaid continuing section and forming a minor loop with the adjacent portion of the remaining loop side, the first loop side having an eye at its 15 outer end that is also angular to the aforesaid plane and beyond which the aforesaid remaining loop side is continued; a second element in the form of a bolt having an eye receiving said remaining loop side and a 15 threaded stem passing through the eye upon the first element; and a nut threaded upon said stem.

20 9. A rung structure including one element in the form of a loop whose base includes one section angular and contiguous to one loop side, and a continuing section connected with and angular to the aforesaid section and forming a minor loop with the adjacent portion of the remaining loop side, the first loop side having an eye at its outer end beyond which the aforesaid remaining loop side is continued; a second element in the form of a bolt having an eye receiving said remaining loop side and a threaded stem passing through the eye upon the first element; and a nut threaded upon said stem.

10. A rung structure including one element in the form of a loop having an angular section at the outer end of one of its sides and an eye at the outer end of this section and angular to the plane of said loop side and this section and whose base includes one section angular and contiguous to the aforesaid loop side and extending therefrom in a direction generally similar to the direction in which the first aforesaid section projects from said loop side, and a continuing section connected with and angular to the aforesaid section and forming a minor loop with the adjacent portion of the remaining loop side, the first loop side having an eye at its outer end that is also angular to the plane and beyond which the aforesaid remaining loop side is continued; a second element in the form of a bolt having an eye receiving said remaining loop side and a threaded stem passing through the eye upon the first element; and a nut threaded upon said stem.

11. A rung structure including one element in the form of a loop whose base includes one section angular and contiguous to one loop side and a continuing section angular to the plane of this loop side and base section and a second element in the form of a bolt assembled with the ends of the loop.

12. A rung structure including one element in the form of a loop whose base in-

cludes one section angular and contiguous to one loop side, a continuing section angular to the plane of this loop side and base section, and an additional continuing section angular to the aforesaid continuing section and forming a minor loop with the adjacent portion of the remaining loop side; and a second element in the form of a bolt assembled with the ends of the loop.

13. A rung structure including one element in the form of a loop having an angular section at the outer end of one of its sides and a section in its base portion contiguous and angular to the aforesaid loop side and extending therefrom in a direction generally similar to the direction in which the first aforesaid section projects from said loop side; and a second element in the form of a bolt assembled with the ends of the loop. 75 80 85

14. A rung structure including one element in the form of a loop having an angular section at the outer end of one of its sides and whose base includes one section angular and contiguous to the aforesaid loop side and extending therefrom in a direction generally similar to the direction in which the first aforesaid section projects from said loop side, and a continuing section angular to the plane of this loop side and base section, and a second element in the form of a bolt assembled with both ends of said loop. 90 95

15. A rung structure including one element in the form of a loop having an angular section at the outer end of one of its sides and whose base includes one section angular and contiguous to the aforesaid loop side and extending therefrom in a direction generally similar to the direction in which the first aforesaid section projects from said loop side, a continuing section angular to the plane of this loop side and base section, and an additional continuing section angular to the aforesaid continuing section and forming a minor loop with the adjacent portion of the remaining loop side; and a second element in the form of a bolt assembled with both ends of the first aforesaid loop.

16. A rung structure including one element in the form of a loop whose base includes one section angular and contiguous to one loop side, and a continuing section connected with and angular to the aforesaid section and forming a minor loop with the adjacent portion of the remaining loop side; and a second element in the form of a bolt assembled with both ends of the first loop. 120

17. A rung structure including one element in the form of a loop having an angular section at the outer end of one of its sides and whose base includes one section angular and contiguous to the aforesaid loop side and extending therefrom in a direction generally similar to the direction in 125 180

which the first aforesaid section projects from said loop side, and a continuing section connected with and angular to the aforesaid section and forming a minor loop with the adjacent portion of the remaining loop side; and a second element in the form of a bolt assembled with the outer ends of the first loop.

18. A rung structure including an element in the form of a loop whose base includes one section angular and contiguous to one loop side, a continuing section angular to the plane of this loop side and base section, and an additional continuing section angular to the aforesaid continuing section and forming a minor loop with the adjacent portion of the remaining loop side.

19. A rung structure including an element in the form of a loop having an angular section at the outer end of one of its sides and a section in its base portion contiguous and angular to the aforesaid loop side and extending therefrom in a direction generally similar to the direction in which the first aforesaid section projects from said loop side.

20. A rung structure including an element in the form of a loop having an angular section at the outer end of one of its sides and whose base includes one section angular and contiguous to the aforesaid loop side and extending therefrom in a direction generally similar to the direction in which the first aforesaid section projects from said loop side, and a continuing section angular to the plane of this loop side and base section.

21. A rung structure including an element

in the form of a loop having an angular section at the outer end of one of its sides and whose base includes one section angular and contiguous to the aforesaid loop side and extending therefrom in a direction generally similar to the direction in which the first aforesaid section projects from said loop side, a continuing section angular to the plane of this loop side and base section, and an additional continuing section angular to the aforesaid continuing section and forming a minor loop with the adjacent portion of the remaining loop side.

22. A rung structure including an element in the form of a loop whose base includes one section angular and contiguous to one loop side and a continuing section connected with and angular to the aforesaid section and forming a minor loop with the adjacent portion of the remaining loop side.

23. A rung structure including an element in the form of a loop having an angular section at the outer end of one of its sides and whose base includes one section angular and contiguous to the aforesaid loop side and extending therefrom in a direction generally similar to the direction in which the first aforesaid section projects from said loop side, and a continuing section connected with and angular to the aforesaid section and forming a minor loop with the adjacent portion of the remaining loop side.

In witness whereof, I hereunto subscribe my name this 8th day of December, A. D., 1923.

HERMAN C. PRIEBE.
